UNITED STATES PATENT OFFICE.

CHARLES GULDEN, OF NEW YORK, N. Y.

CAP FOR MUSTARD-BOTTLES.

SPECIFICATION forming part of Letters Patent No. 271,237, dated January 30, 1883.

Application filed December 19, 1882. (No model.)

To all whom it may concern:

Be it known that I, CHARLES GULDEN, of New York, in the county and State of New York, have invented an Improved Cap for Mustard-Bottles, of which the following is a specification.

Figure 1 is a vertical central section of a mustard-bottle carrying my improved cap, the plane of section being indicated by the line *c c*, Fig. 2. Fig. 2 is a plan or top view of said cap on the mustard-bottle, showing the cap closed. Fig. 3 is a plan view thereof, showing the cap open. Fig. 4 is a vertical cross-section on the line *k k*, Fig. 2; and Fig. 5 is a perspective view of the cap.

This invention relates to a new attachment for mustard-bottles and the like, for the purpose of protecting the contents thereof practically against contact with the air and with impurities; and the invention consists in combining with a concavo-convex spring-clasp, which is adapted to partly embrace the upper bead or rim of the bottle, a hinged cover or lid, as hereinafter more fully described.

In the drawings, the letter *A* represents the usual mustard-bottle, having at its upper part, near its mouth, the outwardly-projecting bead or rim *a*.

B is the spring-clasp, which is of arched form, embracing about three-quarters of a circle, and made of sheet metal or other suitable substance. In cross-section this spring-clasp, as is clearly shown in Fig. 4, is also of arched form, being convex on the outer and concave on the inner side, and by this doubly-arched form—namely, the vertical arch and the horizontal arch of the clasp *B*—it is enabled to be

sprung upon the bead *a* or rim of the bottle and to hold itself securely thereon. Its form allows it to be sprung upon bottles of varying diameters having beads or rims *a* of varying widths. This spring-clasp *B* carries the hinged lid *C*, which is joined to it by a suitable hinge-connection. The lid *C* has or may have at its free end a holding-catch, *b*, which, when the lid is closed down, will catch under that part of the bead *a* which is not embraced by the clasp *B*, as indicated in Figs. 1 and 2.

The lid *C* may contain an aperture or recess, indicated (by dotted lines in Fig. 2,) for the purpose of permitting the spoon that is usually employed in mustard-bottles to be left in the bottle. When a mustard-bottle having this attachment is emptied the attachment can be easily taken from it and placed upon another mustard-bottle, and so used for an indefinite period of time. The attachment will not hermetically seal the bottle, but will practically keep its contents from contact with impurities and preserve them in fresh condition for as long a time as in practice will be required.

I claim—

1. The concavo-convex arched spring-clasp *B* combined with the hinged lid *C*, substantially as and for the purpose herein shown and described.
2. The spring-clasp *B*, combined with hinged lid *C* and catch *b*, substantially as and for the purpose specified.

CHARLES GULDEN.
